SKEWER FOR WINDING MACHINE

Franklin L. Townsend, Rockford, Ill., assignor to Barber-Colman Company, Rockford, Ill., a corporation of Illinois

Filed Nov. 22, 1957, Ser. No. 698,183

4 Claims. (Cl. 242—129.7)

This invention relates generally to skewers for supporting yarn bobbins in a winder or spooler and is an improvement on the bobbin holding structure disclosed in U.S. Patent No. 1,686,102, issued October 2, 1928. In more particularity, the invention concerns a novel skewer readily adapted for use with bobbins of varying size.

The primary object of the invention is to provide a skewer, for use in a winder or spooler, which utilizes an economical, replaceable tip adapting the skewer to handle bobbins having bores of different diameters.

A more detailed object is to construct a skewer having a mounting head, adapted to receive replaceable, economically formed adaptor tips having varying outer diameters, and a set of bobbin holding fingers effective to cooperate with such variably sized adaptor tips so that bobbins having bores of different sizes can be readily handled by the skewer.

Another object is to form the skewer and its replaceable tip so that the tip may be quickly and easily slid onto the skewer, snap-locked into place, and removed by hand when necessary without requiring special tools or equipment.

The invention also resides in the novel arrangement and resilient mounting of the bobbin holding fingers in the skewer which prevents damage to the fingers, for example, if they are forced inwardly, as when the replaceable tip is removed while the fingers are extended to their bobbin holding positions, or forced outwardly as when an attempt is made to install a bobbin without first retracting the fingers.

Other objects and advantages of the invention will become apparent from the following detailed description taken in connection with the accompanying drawings, in which:

Figure 1 is a fragmentary elevation of a winder with a bobbin pocket partially broken away to show a skewer embodying the present invention.

Fig. 2 is an exploded perspective view of the mounting head and replaceable tip of the skewer shown in Fig. 1.

Fig. 3 is a sectional view through the skewer shown in Fig. 1 with a bobbin being fitted thereon.

Fig. 4 is similar to Fig. 3 and shows the bobbin locked on the skewer and the latter shifted to running position.

Fig. 5 is a section through the bobbin taken generally along line 5—5 in Fig. 3 and showing the top of the skewer.

Fig. 6 is a perspective view of the retracting member for the bobbin holding fingers utilized in the illustrated skewer.

Fig. 7 shows the fingers in fully extended position and the yielding which takes place upon premature mounting of a bobbin.

Turning to the drawings, and particularly Fig. 1, the invention is illustrated in connection with a spindle 10 supporting a bobbin B mounted in a winder or spooler 11 having a pocket 14. Yarn unwound from the bobbin passes upwardly through a detector 12.

As covered in Peterson Patent 1,686,102, to swing the

spindle 10 between a loading position and a running position, shown in Fig. 1, the spindle is pivoted on a counterweighted crank arm 20 fixed to a rotatable shaft 21, and is slidably between a pair of guide pins 22, 23. The shaft 21 is rotated by a pinion 25 driven by a slide rack 26 carrying a cam follower 27. For engaging the cam follower a cam 28 is provided on a traveler 29. In operation, movement of the traveler to a position adjacent the pocket 14 causes the rack 26 to be cammed downwardly. This rotates the pinion 25, shaft 21, and crank arm 20 counterclockwise as shown in Fig. 1 and causes the spindle 10 to be drawn downwardly between the guide pins 22, 23. Continued rotation of the crank arm 20 swings the spindle 10 into its loading (dot-dash) position.

For automatic removal of an empty bobbin the bobbin pocket 14 is provided with a floor 31 having a slot 32 within which the spindle 10 swings. When the spindle is drawn downwardly by initial downward rotation of the crank 20, the lower end of the bobbin B strikes the edges of the slot 32 and is lifted from the spindle to fall freely to the right (Fig. 1) into a suitable receiving hopper. When the spindle reaches its loading position, another bobbin may be fitted thereon and rotation of the crank arm 20 completed so as to swing the new bobbin back into the running position.

In accordance with the invention, the details of which are set forth in Figs. 2-7, the skewer 10 includes a shaft 34 having a mounting head 35 which supports a replaceable tip or adaptor 36 having slots for passing a set of bobbin holding fingers 37 having a sufficient stroke as to be capable of operation with a wide range of adaptor diameters. Thus numerous types and sizes of bobbins received from many different spinning mills can be handled by the skewer 10 by simply replacing the tip 36 with a similar tip of suitable size.

Preferably, the tip or adaptor 36 is generally annular in configuration and is provided with a flared skirt portion 41 and a conically tapered end portion 42 so that a bobbin may be quickly and easily telescoped thereover and seated against the skirt portion 41. A plurality of peripherally spaced slots 44 are provided for permitting the bobbin holding fingers 37 to move therethrough and engage a bobbin mounted on the tip 36. Also, the sides of the tip 36 are flattened as at 43 to permit the tip to be drawn through the slot 32 in the floor of the bobbin pocket 14.

The mounting head 35 is preferably cylindrical in outer configuration and is provided with a shoulder flange 46 adapted to seat the tip 36 when the latter is fitted onto the head. The head is also divided by peripherally spaced, axially extending slots 47 which register with the slots formed in the tip. The slots 47 serve the dual function of providing a recess into which the fingers 37 may be retracted and of dividing the head 35 into a plurality of narrow sections 48. In the present instance, the resilience of these sections 48 is utilized to snap-lock the replaceable tip 36 onto the head 35. This is accomplished by providing the tip with an internal annular ridge 49 and the head with a detenting groove 49a. Therefore, when the tip 36 is fitted onto the head 35, the yielding of the head sections 48 will permit the tip to snap into a seated position.

In order to prevent rotation of the tip 36 and to insure registration of the grooves 44, 47 when the tip is snap-locked in position, the tip and the shoulder flange 46 are provided with cooperating tongue and slot 51, 52, respectively. So that the tip 36 may be easily unsnapped from the head 35, the former preferably is provided with a recess 53 which permits insertion of a suitable prying tool.

The fingers 37 are pivoted at their lower ends within the slots 47 for swinging movement between their ex-

tended bobbin holding position (Fig. 4) and their retracted bobbin release position (Fig. 3) under the control of a cam operated plunger 55. As shown, the shaft 34 is hollow and the plunger 55 is slidably mounted and resiliently urged downwardly therein by a compression spring 56 bearing on an enlarged cam follower 57 fixed to the lower end of the plunger. The cam follower 57 rides on a cam 58 carried rigidly by the arm 20 and having a cylindrical outer dwell portion and a recess 59. When the skewer 10 is in its running or Fig. 10 position, the cam follower 57 rests within the recess 59 of the cam 58 and therefore the plunger 55 occupies its lower position. However, when the skewer is swung to its loading position, shown in Fig. 3, the cam follower 57 rides upon the dwell portion of the cam 58 and the plunger 55 is thus thrust upwardly within the shaft 34 against the urging of the spring 56.

As a feature of the invention, the pivoted bobbin holding fingers 37 are resiliently urged toward either their retracted or extended positions in response to sliding movement of the plunger 55. For retracting the fingers, an internal slide 61 is provided, slidably mounted on a rod 63 and biased upwardly by a spring 62 which presses against the upper end of the plunger 55. The slide 61 is provided with peripherally spaced wings or abutments 64 adapted to extend radially into the slots 47 so as to underlie the fingers 37. The abutments have inwardly facing surfaces which engage the outer edges of the fingers to swing the fingers 37 inwardly under the resilient urging of the compressed spring 62.

For resiliently urging the fingers 37 into their extended position the plunger rod 63 is fixed to the plunger 55 and an actuating block 65 is provided at the outer end thereof and disposed so as to engage the fingers 37 above their pivot points. Downward sliding movement of the plunger 55, under the urging of the spring 56, causes the block 65 to resiliently urge the fingers 37 toward their extended, bobbin holding positions and into engagement with the bobbin B fitted on the tip. It will be understood that the spring 56 is stronger than the spring 62 so that the former is effective to overcome the force exerted by the latter, when the cam 58 permits the plunger to move downwardly.

It will be observed that the fingers 37 are resiliently biased, rather than rigidly forced, into both their extended and retracted positions. Thus inadvertent inward movement of the fingers, such as would occur if a bobbin were forcibly removed while the fingers were extended, will simply swing the fingers against the block 65 with yielding of the spring 56. Conversely, if an attempt is made to slide a bobbin onto the skewer with the fingers extended (see Fig. 7) the fingers simply swing against the abutment member 61 accompanied by yielding of the spring 62.

Although any number of variably sized replaceable tips 36 can be utilized with the skewer 10, it has been found that with a minimum of three different tips all bobbins in current commercial use can be handled by the skewer. Adapting the winder to handle bobbins of varying size merely involves lifting one replaceable tip from the mounting head 35 and snapping another, suitably sized, tip in place. Heretofore, it was necessary to substitute an entirely different skewer each time such a change was made and this operation was both time consuming and expensive since it required utilizing a complete set of skewers, including the bobbin holding finger actuating mechanisms, rather than merely a set of economical, replaceable tips.

I claim as my invention:

1. A bobbin supporting skewer for handling bobbins having bores of varying diameter comprising, in combination, a hollow shaft having a mounting head at one end, a plurality of bobbin holding fingers carried on said head and movable between retracted and extended positions, a replaceable tip mounted on said head and

70
75

having an outer diameter corresponding to the bore size of the bobbin to be handled, said tip and said head having respective mating portions to resiliently snap-lock said tip on said head and prevent relative rotation, said tip and said head also being formed to provide an intermediate recess when snap-locked together permitting insertion of a tool for readily separating the tip from the head, said tip having a plurality of openings aligned with said fingers so that the fingers may extend through said openings into engagement with a bobbin fitted on said tip, and a plunger slidably mounted in said shaft having means for retracting or extending said fingers upon axial movement of the plunger.

2. A bobbin supporting skewer for handling bobbins having bores of varying diameter comprising, in combination, a hollow shaft having a generally cylindrical mounting head at one end, said head being divided by peripherally spaced and axially extending slots forming narrow resilient head portions parallel to one another, a bobbin holding finger pivoted in each of said slots and swingable between retracted and extended positions, a generally annular replacement tip slidably fitted over said head portions and having an outer diameter corresponding to the bore size of the bobbin to be handled, said tip and said resilient head portions having interengaging detent elements snap-locking the tip on said head, said tip having a plurality of slots aligned with said fingers so that the fingers may swing through said slots into engagement with a bobbin fitted on said tip, and a plunger slidably mounted in said shaft having means for retracting or extending said fingers upon axial movement of the plunger.

3. A bobbin supporting skewer for handling bobbins having bores of varying diameter comprising, in combination, a hollow shaft having a mounting head with an outer diameter slightly less than the bore of the sizes of bobbins to be handled, a plurality of bobbin holding fingers carried on said head and movable between inward and outward positions, said head having a plurality of slots aligned with said fingers so that the fingers may extend through said slots into engagement with a bobbin fitted on said head, first spring means for urging said fingers inwardly, a plunger slidably mounted within said shaft, a cam having a dwell portion and a recess, second spring means for biasing said plunger against said cam, and an element on said plunger for engaging and urging said fingers outwardly when said plunger is aligned with said cam recess, the second spring means being stronger than said first spring means so that the setting of the cam determines toward which of said positions the fingers are resiliently urged.

4. A bobbin supporting skewer for handling bobbins having bores of varying diameter comprising, in combination, a hollow shaft having a mounting head at one end, a plurality of bobbin holding fingers carried on said head and movable between inward and outward positions, a replaceable tip mounted on said head and having a flared seating surface for accommodating a range of bore sizes of the bobbins to be handled, said tip having a plurality of slots aligned with said fingers so that the fingers may extend through said slots into engagement with a bobbin fitted on said tip, a first resiliently biased plunger member for urging said fingers outwardly, a second resiliently biased plunger member for urging said fingers inwardly, and a cam for operating upon one of said plunger members.
